GARMENT

Henry Hill Collins, Bryn Mawr, Pa.

Application March 16, 1942, Serial No. 434,817

2 Claims. (Cl. 2-92)

This invention relates to an improvement in garments, more particularly vests.

It is the object of this invention to provide a vest or similar garment adapted to supplement the usual wearing apparel to provide protection against wind and cold. The garment is intended primarily for emergency wear by members of the armed forces, or of civilian defense agencies, and by refugees and others who may be exposed to wind and cold without clothing entirely adequate for such exposure; but may also be used as additional protection against the weather by anyone.

It is thus the object of this invention to provide a garment which can be produced readily in quantity at low cost and without consuming vital war materials, which will have a relatively long useful life, and which can be readily used to supplement the usual clothing without undue bulkiness.

These objects are attained in accordance with my invention by providing a garment formed from two layers of light weight cloth secured together along their edges, and so stitched as to form a plurality of pockets, extending in the aggregate over substantially the entire area of the garment, the pockets all opening through slits formed in one of the layers of cloth, preferably to the inside of the garment as worn.

Windproof material of any desired thickness, as newspaper, may be placed in the pockets to give the needed protection, and replaced as required substantially without expense.

The manner in which these objects may be accomplished is further set forth by the following description of a preferred embodiment of my invention shown in the accompanying drawing, in which:

Figure 1 is a front view of a vest in accordance with my invention, shown in wearing position.

Figure 2 is a diagrammatic sectional view on the line 2-2 in Fig. 1, omitting the inner of the front flaps.

Figure 3 is a diagrammatic sectional view on the line 3-3 in Fig. 1.

Figure 4 is a detail sectional view through one of the pockets, showing newspaper pages in place therein.

Figure 5 is a view of newspaper pages folded for insertion into one of the pockets.

And Figure 6 is a plan view of the vest in extended position, showing the manner of insertion of newspaper pages into the pockets.

As shown in Figure 6 the improved vest in ac-

cordance with my invention is formed of a rear panel 11 of generally trapezoidal shape, secured to each side edge of which are front panels 13 of generally triangular shape. Armholes 15 are formed on the line of juncture of the front and rear panels. A tape 17 secured to the free side edge of one of the front panels, and a second tape 19 secured at the seam between the opposite front panel and the rear panel enable the garment to be secured in place upon the wearer, who simply ties the two shapes together where they meet—see Fig. 1.

As shown in Figs. 2 and 3, the several panels are formed from two layers, 21, 23 of light weight fabric, as cotton sacking or the like, secured together at the edges by turned seams 25. Two pockets 27, 29 are formed in the rear panel 11; and two similar pockets 31, 33 in each of the front panels 13. The lower pockets 33 in the front panels are defined at one side and the bottom by a line of stitching 35 spaced inwardly from the free edges of the panels. The upper pockets 31 are defined at the bottom by a line of stitching 37, also defining the top of the pockets 33, at the top by a second line of stitching 39, and along one side by a line of stitching 40. Pocket 29 extends to the very bottom of panel 11, and is separated from pocket 27 by a line of stitching 41. A second line of stitching, 43, defines the top of pocket 27.

Slits 45 cut in the inner layer of fabric 23 at the top of each of the pockets afford access to the pockets. The slits 45 are preferably shorter than the full width of the pockets. If desired the material may overlap the slits 45, so as to conceal the openings.

Newspaper pages P folded in the manner shown in Fig. 5 may easily be inserted in the various pockets as indicated in Fig. 6. Any desired thickness of paper may be used. The paper once fully inserted in the pocket may be opened up to the shape shown by the line 47 in Fig. 6, and so will be held securely within the pocket without danger of displacement or slipping out.

Since the pockets 33 do not extend quite to the bottom of the front panels, the wearer may sit without being discomfited by the stiffness of the newspaper, as the lower edge of the front panels flexes readily.

What I claim and desire to protect by Letters Patent is:

1. A vest comprising a rear panel and, extending from the respective side edges thereof, two front panels each of which is so substantially wider at the bottom than at the top that, when

in position on the body of the wearer, the two front panels overlap to form a front covering of double thickness of approximately triangular shape, each panel being formed of at least two layers of cloth joined together to form a pocketed area, the inner layer of each panel having a slit near the top of the panel extending across the panel from near one side edge thereof to near the other side edge thereof and having another and longer slit between its top and bottom extending across the panel from near one side edge thereof to near the other side edge, thereby providing in each panel a wider lower pocket and a narrower upper pocket, the two layers of each panel being secured together to close the upper pocket from the lower pocket, each slit affording an opening through which rectangular shaped paper, having a width approximating the width of its slotted opening, may be inserted into the corresponding pocket and therein occupy an area not much less than that of the pocket; whereby the vest throughout the greater part of its area may be heat-insulated by rectangular shaped paper insertions.

2. A vest comprising a rear panel and, extending from the respective side edges thereof, two front panels each of which is so substantially wider at the bottom than at the top that, when in position on the body of the wearer, the two front panels overlap to form a front covering of

double thickness of approximately triangular shape, each panel being formed of at least two layers of cloth joined together to enclose a pocketed area approximating the area of the panel, the inner layer of the rear panel having one or more slits extending across the panel from near one side edge to the other side edge to allow the insertion of one or more flat rectangular shaped paper structures, the inner layer of each front panel having a slit near the top of the panel extending across the panel from near one side edge thereof to near the other side edge thereof and having another and longer slit between its top and bottom extending across the panel from near one side edge thereof to near the other side edge, thereby providing in each front panel a wider lower pocket and a narrower upper pocket, the two layers of each front panel being secured together to close the lower pocket from the upper pocket, each slit affording an opening through which rectangular shaped paper structures, having a width approximating the width of its slotted opening, may be inserted into the corresponding pocket and therein occupy an area not much less than that of the pocket; whereby the vest throughout the greater part of its area may be heat-insulated by rectangular shaped paper insertions.
